(57) **CLAIM**

The ornamental design for a motor vehicle, toy replica and/or other replica, as shown and described.

DESCRIPTION

FIG. 1 is a top, front, and right side perspective view of a motor vehicle, toy replica and/or other replica showing my new design;

FIG. 2 is a rear perspective view thereof;

FIG. 3 is a front elevation view thereof;

FIG. 4 is a rear elevation view thereof;

FIG. 5 is an elevation view thereof taken from the left side, the right side being a substantial mirror image thereof; and, FIG. 6 is a top plan view thereof.

The broken lines shown throughout the drawing views are for environmental and illustrative purposes that form no part of the claimed design.

1 Claim, 6 Drawing Sheets
